(57) **CLAIM**

The ornamental design for a zippered propane tank sleeve, as shown and described.

DESCRIPTION

FIG. 1 is a top plan view of a zippered propane tank sleeve according to my design;

FIG. 2 is a plan view thereof; and,

FIG. 3 is a view of a bottom plan view of a zippered propane tank sleeve as illustrated in FIGS. 1 and 2, according to my new design.

The broken line showing is included for the purpose of illustrating environment and forms no part of the claimed design.
